ABSTRACT

An automatic splicing apparatus for splicing yarn by wrapping filament around the yarn, comprising a housing and a drive means mounted therein which rotates a filament wrapping wheel. The filament wrapping wheel has a filament supply mounted thereon and clamping and cutting means secured to the housing hold and cut the yarn being spliced. A filament holder means mounted to the housing retains an end of the filament during the slicing cycle and cuts the filament at the end of the cycle.

AUTOMATIC SPLICING APPARATUS

The present invention generally relates to an improved apparatus for joining together textile yarns without knotting the same, and more particularly, to an automatic yarn splicing apparatus.

In the manufacturing of textiles there is a frequent need to splice together the ends of various yarns being processed. For example, if there is a break in the yarn being processed or if the supply package of yarn is exhausted and a succeeding supply package of yarn must be joined to the yarn of the first supply package, the two free ends of the yarns must be rejoined to provide continuity to the yarn. Sometimes, the processing must be stopped while the operation of joining the ends of yarn is completed and, hence, any such joining must be accomplished quickly and with a minimum of delay.

Previously, the joining of yarns was often accomplished by tying a knot in the free ends of the yarns to be spliced, the knot either being tied by hand or by use of some suitable mechanical equipment designed for the purpose. There are many occasions in the processing of yarns and the manufacture of textiles when a knot in the yarn is not desirable. For example, a knot is normally quite bulky in relation to the diameter of the yarn being tied, and, thus, with its bulk and its lack of ability to properly flex, the knot will make the yarn vulnerable to being trapped and/or broken as the yarn passes through small eyelets or apertures such as normal reed spacing in the weaving operation. Additionally, such knots can be objectionable in the finished textile produced as they provide imperfections in the surface of such fabric. Currently, these knots are hand pulled from the surface of the fabric when the fabric is a high quality material.

The splicing of the ends of yarn together has been used in the manufacture of textiles primarily by utilizing splicing compounds, the splicing compounds being applied to overlapping free ends of the yarns and the yarn ends rolled together. This type of splicing has disadvantages in that the compound is quite tacky when applied and there is a time delay involved in waiting for the splicing compound to dry. Additionally, once the splicing compound has dried, an undesirably hard joint surrounds the yarns, thus preventing this part of the yarn from folding in limp convolutions about other yarns during and/or after weaving. The hard dried splicing material quite often hangs up on small eyelets, reed dents or the like thus causing the yarn to break or the material to dye differently.

An additional means of splicing yarns which has developed over the recent years, utilizes a wrapping thread or filament for wrapping the two ends of yarn together. The prior apparatus which has been previously utilized for making this type of splice has been quite cumbersome and stationary thus limiting its adaptability of use in the textile plant or having the disadvantage of causing the yarns to be spliced to have a migration or loss of twist at the splice.

The present invention provides an improved automatic splicing apparatus which is capable of use on yarns regardless of whether the yarns are spun from natural fibers, synthetic fibers, animal fibers or mineral fibers, and can splice any yarn from fine count spun and worsted yarns up to very coarse carpet yarns. The resulting splice or joint initiated by the present invention is as strong or stronger than the strength of the yarns being joined, with the splice retaining the flexibility to a degree similar to the flexibility of the yarns being spliced so that the splice does not interfere with the fold around other yarns of the final woven fabric in which the yarn is used.

The use of the present invention saves time, labor costs and enables a high quality product to be manufactured in a shorter time than with machines now in use.

These and other objects and advantages of the invention will appear more clearly from the following specifications in connection with the accompanying drawings in which:

FIG. 1 shows a plan view of the automatic splicer apparatus with the rack cylinder broken away for clarity;

FIG. 2 is a side view of the automatic splicer apparatus shown in FIG. 1;

FIG. 3 is a cross sectional view of FIG. 1 taken along line 3 — 3;

FIG. 4 is a cross sectional view of FIG. 1 taken along line 4 — 4;

5 FIG. 5 shows a plan view of the wrapping wheel assembly of the automatic splicer apparatus;

FIG. 6 is a cross sectional view of FIG. 5 taken substantially along the line 6 — 6;

10 FIG. 7 is a cross sectional view of FIG. 5 taken substantially along the line 7 — 7;

FIG. 8 is a cross sectional view of FIG. 1 taken along line 8 — 8, showing the wrapping wheel drive means;

FIG. 9 is a side sectional view of FIG. 2 showing the auxiliary drive means;

15 FIG. 10 is a sectional view of FIG. 4 showing the cam assembly drive means;

FIG. 11 is a partial cross sectional view taken from FIG. 1 along line 11' — 11' showing the cam plate assembly;

20 FIG. 12 shows an end view of cam plate assembly shown in FIG. 11 in relation to the apparatus;

FIG. 13 is a plan view of the automatic splicer apparatus with portions taken away for clarity;

FIG. 14 is a cross sectional view of FIG. 13 taken along line 25 14 — 14;

FIG. 15 is a top plan view of the upper cut finger assembly;

FIG. 16 is an end elevation of the upper cut finger assembly shown in FIG. 15;

FIG. 17 is a side view of the lower cut finger assembly;

30 FIG. 18 is an end elevation of the lower cut finger assembly shown in FIG. 17;

FIG. 19 is a top plan view of the clamp finger assembly;

FIG. 20 is an end elevation of the clamp finger assembly in FIG. 19;

35 FIG. 21a-h shows the sequential steps of the filament wrap during the splicing cycle;

FIG. 22 is a graph illustrating the cam sequence of the clamping finger assembly;

FIG. 23 is a side view of the filament holder assembly;

40 FIG. 24 is an end elevation of the blade assembly of the filament holder assembly shown in FIG. 23;

FIG. 25 is a side view of the filament holder assembly mounted in the automatic splicer apparatus;

45 FIG. 26 is a perspective top view of the automatic splicer apparatus showing the filament holder assembly; and

FIG. 27 is a schematic view of an electric circuit operating said automatic splicer apparatus.

The present automatic splicer invention is preferably designed to replace the knot tying mechanism in a machine similar to the ones which are shown by U.S. Pats., Nos. 3,077,311 and 3,061,216. A machine of this type travels on a way bed and services the winding stations of an autocorder machine which winds yarn onto large spools from smaller bobbins. The automatic splicer apparatus can however be used in machines of different construction. If the yarn breaks during the winding operation, the machine is signaled to stop at that station and tie the broken ends. If the bobbin has simply run out of yarn, the machine will automatically change bobbins, tie the yarn ends of the full bobbin to the spool's yarn, and signal the spool to resume the winding operation.

The automatic splicing device, as disclosed by FIGS. 1-4, is designed to fit in the area which is occupied by a knot tying mechanism in machines similar to the above mentioned machines. When signaled, the apparatus will splice the yarn ends together with a low temperature, water-soluble filament, which will be washed out after the yarn is woven into cloth, leaving the splice indiscernable in the material.

On the present automatic splicing machine, when a broken thread or yarn is detected, the traveling splicer head stops at that station, picks up the broken ends of the yarn or thread and places them in parallel relationship in the wrapping wheel assembly for splicing. The present invention is primarily concerned with splicing the yarn after it has been placed in the 75 wrapping wheel assembly.

The splicing of the yarn or thread is controlled by a cam in the traveling splicer head. An actuator lever 600, having a contact pin 602, as is shown by FIG. 25, is positioned on the end of the shaft of this cam and rotates to operate electrical switch SW1. This switch stops the drive motor 612 of the traveling splicer head and initiates the wrapping cycle.

The wrapping is started by the rotation of the wrapping wheel assembly 100. The rotatable wrapping wheel assembly 100, comprises a drive body assembly 102 and an insert plate assembly 104, as is shown by FIGS. 5, 6 and 7. The insert plate assembly 104 is held in place on the drive body assembly 102 by a retaining clip or spring 106, which allows the insert plate assembly to be easily removed from the drive body assembly by depressing the two tabs or ends 108 of the clip or spring 106. The insert plate assembly 104 comprises an insert plate 110 and a filament, thread or yarn cartridge assembly 112 mounted or secured thereon. The filament cartridge assembly 112 is held in place or secured to the insert plate 110 by a mount or bracket 116. The mount 116 is secured to the insert plate 110 by welding, screwing means, riveting, adhesives or other suitable means and preferably has a substantially L-shaped arm or support 114 extending therefrom which supports a bobbin or filament supply holder 120. If desired, the mount 116 can support a substantially U-shaped arm or post to support the bobbin or spool 120. The bobbin or spool 120 is preferably flanged at 119 and a outer case 118 which can be of plastic construction is snapped or slid over the end flanges. The bobbin 120 is preferably able to rotate on arm 114 or on a projection extending therefrom. It is of course obvious that the bobbin does not have to be covered but that the case 118 gives greater protection to the filament 122.

The wrapping filament thread or yarn 122 which is wound around bobbin or spool 120 is preferably made from a water soluble material such as sodium alginate, hydroxyethyl amylose, polyvinyl alcohol, and the like and is preferably around 0.002 inch in diameter. By making the wrapping filament thread or yarn 122 of a water soluble material, the splice made on the yarn ends may be dissolved out when the woven fabric or the like passes through a wet finishing operation. In other words, the wrapping filament 122 can readily be removed from the splice during any subsequent wet processing of the material woven from the yarn such as a desizing process or the like. The filament 122 which forms the splice S, shown in FIGS. 21a-h, is wound around the bobbin or spool 120 and is fed outward between the plastic case 118 and the bobbin or spool 120 or through a center hole in one of the flanges 119 of the bobbin. Regardless of the embodiment used, the filament preferably passes through an eyelet 124, preferably of pigtail construction and which may be secured to mount 116 or to the insert plate 110. The filament 122 is placed in contact with tension means 126 which is preferably adjustably mounted on the insert plate 110 by thread means. The tension on the filament is derived by tightening the tension means 126, compressing spring 128 which urges plate 127 against the filament, increasing the tension on filament 122, or by loosening the tension means and thus lessening the tension on filament 122. The tension means applies a uniform constant tension on the splicing filament, yarn or thread being carried by the bobbin or supply means as the splice is being made, regardless of the amount of splicing filament, thread or yarn remaining on bobbin 120. If desired, the filament, thread or yarn of the bobbin can be adjustably tensioned on the bobbin by tension means which applies drag or friction to the bobbin thus resisting its tendency to rotate. Irregardless of the form of tension means applied to the filament, the filament 122 preferably passes through a filament guide 130 which guides the filament during the wrapping or splicing process. It should be noted that the wrapping filament 122 develops a high wrapping torque because of the rotation of the wrapping wheel assembly and even though the wrapping thread or filament may not possess high strength properties, the resulting splice or joint will be as strong or stronger than the strength of the yarns being joined. Additionally, the splice retains the flex-

ability to a degree similar to flexibility of the yarns or threads being spliced and, thus, the splice does not interfere with the fold around other yarns of the final woven fabric in which the yarn or thread is used. It should also be noted that if desired, the insert plate 110 can have optional weight balances 135 to provide a uniform rotational plane for the wrapping wheel assembly, if for any reason it is out of balance.

When the threads or yarn Y and Y', as shown in FIG. 21a-h are positioned parallel and coaxial with the axis of rotation of the wrapping wheel assembly 100 they do not twist about one another. When the filament or thread 122 orbits about Y and Y' thus delivering the splicing filament 122 from its bobbin or spool 120, the torque of the splicing filament 122 is sufficiently great so that the filament is embedded into the bulky yarns Y and Y' being spliced, and the splice S compacts the pair of yarns to a diameter resembling one of the component yarns Y or Y'.

The drive body assembly 102 which holds the insert plate assembly 104, can be an integrally cast or machined unit which is suitably constructed to receive the insert plate 110 of the insert plate assembly 104 and the retaining ring or clip 106. However, the drive body assembly can be constructed in sections if this is desirable. If desired, gear teeth portions of the assembly 102 can be removably secured to the drive body assembly for easy replacement because of wear or breakage. The drive body assembly 102 preferably has an aperture or hollow arcuate section 133 to accommodate yarn Y and Y' coaxial with the axis of rotation of the wrapping wheel assembly 100, an outer grooved rim 132 and a plurality of gear teeth 134 or gear teeth segments which cooperate with the drive means.

The wrapping wheel assembly 100 preferably has a pie-shaped segment 137 removed from the insert plate 110 and drive body assembly 102, in addition aperture 133 to insert the yarn Y and Y' for splicing. Because of this open segment in the drive body assembly 102 and consequent lack of gear teeth it is necessary to have two driving pinion gears 200 and 202 as shown in FIGS. 5 and 14 to rotate it. The driving pinion gears are mounted on roller bearing means 205 which rotate around pinion shafts 203. The pinion shafts 203 extend through and are supported by the upper wrapping wheel support cover 145 and the lower wrapping wheel support cover 147. The driving pinion gears 200 and 202 are spaced sufficiently far apart so that at least one of the pinion gears will always engage the rotating gear teeth 134 on the drive body assembly 102 regardless of its position. The driving pinion gears are preferably constructed to have an extension or keeper 207 which slidably moves in a groove 109 on the outer surface of the outer rim 132. The action of the drive pinion gear extension or keeper 207 in channel or groove 109 keeps the wrapping wheel assembly smoothly rotating and the gear teeth of the wrapping wheel assembly 100 and pinion gear 200 and 202 aligned and uniformly engaging each other. Side rollers 136 and 138, as shown by FIG. 13, and end rollers 140 and 142, as shown by FIG. 1, keep the wrapping wheel assembly 100 smoothly rotating on an even axis and in connection with driving pinion gears 200 and 202. The rollers 136, 138, 140 and 142 are rotatably mounted on shafts 135 which are supported by upper wrapping wheel support cover 145 and lower wrapping wheel support cover 147. Rollers 136, 138, 140 and 142 rotate around shafts 135 on bearing means 139. When the wrapping wheel assembly is rotating, its periphery can be contacted at six places, namely by pinion gears 200 and 202 and rollers 136, 138, 140 and 142. The open or substantially pie-shaped segment 137, which is removed from the wrapping wheel assembly, preferably comprises an approximately 50° segment of the wrapping wheel assembly, while the pinion gears 200 and 202 are preferably placed 60° apart. It is apparent, of course, that the pinion gears can be placed in any position, so long as they operate to turn the wrapping wheel assembly. The gear tooth segment of the wrapping wheel preferably contains 54 teeth and is cut from a 68-tooth gear. Since the wheel driving gear 204 has the same number of teeth

as the wrapping wheel would have if it were a solid gear, the wheel driving gear 204 always maintains an exact angular relationship to the wrapping wheel assembly 100.

The wrapping wheel assembly is rotated by the gear drive means shown by FIGS. 8, 9, 10 and 11.

A motor, not shown, operating from a suitable power source turns or rotates the main drive shaft 206 which is mounted in a plurality of ball bearing means 208 and 210, as shown by FIG. 8. Ball bearing means 208 is positioned in the drive shaft housing 212 and is kept in position in housing 212 by clip means 214 which surrounds drive shaft 206. Ball bearing means 210 is positioned in housing 212 by abutting against a drive gear 218 which is secured at the end of the drive shaft 206. The drive shaft 206 has an auxiliary gear 216 mounted thereon which may be secured to the drive shaft by pin means 217. However, any other suitable means of securing auxiliary gear 216 to the drive shaft 206 can be used. Gear 218 is mounted on the end of shaft 206 and secured thereto by key means 219 so that the drive gear 218 rotates with shaft 206 and intermeshes with output gear 220, driving output gear 220. Output gear 220 is preferably secured to a varied diameter staged output shaft 222 by key means 224. It should be noted that while the key means mentioned are preferred, any other suitable securing means can be used. Output shaft 222 is mounted in roller bearing means 226 and 228 which are positioned against the output shaft housing 230 by abutting against a wall formed by the increased diameter stages of output shaft 222 and respective clip means 232 and 234. Gears 218 and 220 are preferably miter gears and as mentioned are secured to their respective shafts by suitable means such as keys 219 and 224. The key means preferably fit in a slot in the shaft. The output shaft 222 which is turned by the cooperation of gears 218 and 220 rotates a wheel drive gear 204 which is secured to output shaft 222 by key means 236. As shown by FIGS. 13 and 14, the wheel drive gear 204 drives pinion drive gears 200 and 202 which in turn rotate the wrapping wheel assembly 100. The wheel drive gear 204 has pin means 238 projecting therefrom which is secured to the wheel drive gear and rotates as the wheel drive gear 204 rotates. A positioning pinion gear 240 is mounted above the drive gear and is mounted on output shaft 222 by roller bearing means 242 and 244, which contact the outer surface of the output shaft. Positioned inside the positioning pinion gear 240 is a roller clutch 246 which is constructed to contact the outer surface of output shaft 222 in only one direction. When the teeth of rack 404 engage the teeth of the pinion gear 240, because the rack is carried forward by piston 402, the roller clutch 246 engages the outer surface of the output shaft 222 thus turning the wheel drive gear 204. When the rack 404 is carried in the opposite direction by the retraction of piston 402 which is activated by cylinder 400, the roller clutch 246 disengages from the outer surface of output shaft 222 allowing the positioning pinion gear to rotate on its roller bearing means. Auxiliary drive means which are run off the wrapping wheel drive means, drive cams which control the fluid or air cylinders which activate the cutting and clamping means and the cam which causes these cutting and clamping means to oscillate up and down during the filament wrapping segment of the splicing cycle.

As shown by FIGS. 4, 8 and 9, an auxiliary drive gear 216, mounted on the drive shaft 206 by pin or other suitable means 217, engages and turns a second auxiliary drive gear 248 which is suitably secured to a worm shaft 250. The worm shaft 250 is mounted in roller bearing means 253 and 254 which are suitably positioned in housing 212. The rotating of worm shaft 250 turns a worm 252 which is secured to the worm shaft 250. As shown by FIGS. 8a and 10 the rotation of worm 252 turns a worm gear 256, which engages worm 252, the worm gear 256 being secured by key means 257 to a shaft 258. The shaft 258 is mounted in roller bearing means 260 and 262 which are suitably positioned in housing 212 by means of spacers 264 and 266. Spacer 264 substantially surrounds shaft 258 between roller bearing means 260 and worm gear 256 while

spacer 266 substantially surrounds shaft 258 between roller bearing means 262 and worm gear 256. A cam drive gear 268 is mounted at one end of shaft 258 and secured by key means 270 and is preferably located outside of the housing 212. It is noted that cam drive gear 268 can be located within housing 212. The cam drive gear 268 is kept in place on the shaft 258 by key means 270 which preferably fits into a slot on the shaft and a spring clip 272 which surrounds the outer surface of the shaft. As shown by FIGS. 9 and 11, the rotation of cam drive gear 268 drives cam gear 274 which is mounted to a cam drive shaft 276 and secured by key means 278. A cam plate assembly 275 is secured to cam gear 274 by pin means 290. Cam drive shaft 276 is mounted in roller bearing means 280 and 282 which are positioned against the housing 212 by a spacer 284. The cam plate assembly 275, as shown by FIGS. 11 and 12, comprises a cam hub 286 which surrounds a portion of shaft 276 and flanges outward as shown by 288. The cam hub 286 is secured by pin means 290 to cam gear 274. The cam hub flange 288 serves as a spacer for cam plate 291. Cam plate 291, cam plate 292 and cam plate 293 are mounted on cam hub 286 and are kept from rotating on the cam hub by pin means 290 which extends through an aperture in each cam plate. Cam plates 291 and 292 are separated from each other by spacer means 294 and cam plates 292 and 293 are separated from each other by spacer means 295. A spring clip 296 around hub 286 holds cam plate 293 against spacer means 295, and another clip 273 holds hub 286 in position on shaft 276. On the other end of shaft 276 and preferably outside housing 212 is an oscillating cam 297 which is secured to shaft 276 by key means 298. The oscillating cam is constructed to contact cam follower 277, as shown by FIGS. 1 and 4. The oscillating cam 297 is held in place on the shaft by spring clip 299 which surrounds shaft 276. The oscillating cam 297 operates to cause the cutting and clamping means to oscillate up and down during the splicing cycle. FIG. 12 shows a sectional view of the cam plate assembly operating the timing switches.

It should be noted that in the auxiliary gearing spur gears can be substituted having 1 1/4 ratio and a worm set of a 40-1 ratio having a nominal reduction of 50-1. These change gears can be mounted on the outside of the gear box. Additionally, two 27-toothed gears can be used which provide a 1-1 external ratio or a 50-1 total. Another set, one a 24-toothed gear and one a 30-toothed gear can provide an external ratio of 1.25 - 1 or 0.8 - 1. By using these ratios it is easily shown that the overall ratio with the auxiliary gears can go from 40-1 to 62 1/2 - 1. Therefore, 40, 50, or 62 1/2 wraps of filament for the splice are available depending on the gear ratio chosen.

Positioned relative to the wrapping wheel assembly 100 are clamping and cutting fingers as shown by FIGS. 21a-h.

In the splicing apparatus these respective fingers or assemblies clamp the ends of the threads or yarn that are parallelly and axially positioned in the wrapping head assembly, and cut off the ends of each thread or yarn during the splicing cycle at a certain time which is controlled by cam plate assembly 275. The cut thread or yarn ends are then sucked up or disposed of by suitable thread disposal means. The action of the fingers or cutting and clamping assemblies is shown by FIGS. 21 and 22. FIG. 14 shows the position of the clamp finger assemblies 300 and 302, one above the wrapping wheel assembly 100 and the other below the wrapping wheel assembly. Clamp finger assembly 300 holds the threads or yarn to be spliced in cooperation with the upper cut finger assembly 304 and clamp finger assembly 302 holds the threads or yarn to be spliced in cooperation with lower cut finger assembly 306. The four gripping or clamping cylinders 310, 340, 341 and 370 operate the start of the wrapping cycle. The cutting cylinders 312 and 372 operate later in the cycle at a precise time according to the position of the thread and set number of wraps of filament 122. These functions are controlled by the cam plate assembly 275 which is rotated in relation to the number of turns of the wrapping wheel.

The location of the clamp finger assemblies 300 and 302 and the upper cut finger assembly 304 and the lower cut finger assembly 306 is shown in FIGS. 14 and 21 with the clamping finger assembly positioned in respect to the number of wrapping wheel revolutions shown in cam sequence by the diagram of FIG. 22. The upper cut finger assembly 304 is used above the wrapping wheel assembly 100 to clamp and make the second cut on one of the threads which is being spliced. The upper cut finger assembly 304, as shown by FIGS. 15 and 16, comprises fluid or air cylinders 310 and 312 which are secured to bracket plate 313. The bracket plate 313 has apertures in it which enables pin means 315 to be inserted therethrough to secure the bracket to the apparatus housing as shown by FIG. 1. Pistons 314 and 316 are slidably seated in fluid or air cylinder 310 and 312 respectively. A link arm 318 is secured to clamping piston 314 by a pin means 320. The other piston 316 which is the cutting piston, has secured thereto linkage 324 by pin means 326. Linkage 324 is in turn secured at 327 by a rivet or other suitable means to a second linkage 328. Pin means 320 and 326, preferably, have annular channels or grooves in their shafts so they can be preferably maintained by a "C" type washer or clip. If desired, a standard cotter pin or other securing means could be used. The second linkage 328 is held against link arm 318 by the urging of spring means 330 which surrounds rotatable shaft 322. Spring means 330 is held in place by collar 332. Shaft 322 extends through apertures in second linkage 328 and sleeve of link arm 318. Shaft 322 has an angular configuration where it passes through the aperture of second linkage 328, the configuration corresponding to the angular aperture of second linkage 328. This relationship enables shaft 322 to be rotated by activation of the cutting piston 316. However, any other desired relationship between the second linkage and the shaft which will allow the second linkage to be rotated with the shaft can be utilized.

As previously mentioned, piston 314 should be considered as the clamping piston, as the movement of this piston activates link arm 318 which in turn moves clamp plate 319 in the sequence shown in FIGS. 21a-h. As shown by FIGS. 14 and 21a-h, the clamp plate 319 moves in relation to the stationary thread holding body 321 which is secured to the upper cut finger assembly housing 323 to provide stability for the assembly. To provide additional support and protection against vibration a post 325 is secured to housing 323. Post 325 is preferably channeled to hold spring means 327 which has one end secured to the post 325 and its other end secured to the apparatus housing. Piston 316 should be considered the cutting piston, as its activation by fluid or air cylinder 310 provides the cutting movement for rotating shaft 322 and cutting blade 329 which is secured thereto to cut the thread or yarn Y, Y'. Cooperating with the cutting finger assembly 304 is an upper clamp finger assembly 300 which is shown by FIGS. 19 and 20. The clamp finger assembly comprises an air or fluid cylinder 340 secured to the apparatus housing, a piston 342 slidably mounted therein and a link arm 344 which is connected to piston 342 by pin means 346. The pin means 346 preferably has an annular channel or groove in its shaft so that it can be maintained in position by a "C" type washer or clip. If desired, a standard cotter pin or other suitable means could be used to maintain pin 346 in position. The link arm 344 which is preferably a sleeve with an arm secured thereon rotatably abuts stationary thread holder 347 which is secured to clamping assembly housing 356. The stationary thread holder 347 and link arm 344 have apertures therethrough into which a shaft 352 is inserted. Pin means 345 is inserted through an aperture in link arm 344 and an axially coaligned aperture in shaft 352, causing shaft 352 to rotate by the action of link arm 344 and pin means 345 when piston 342 is activated. At one end of the shaft is a clamp plate 348 which is kept against the outer edge of thread holder 347 by spring means 350 which surrounds shaft 352. The spring means 350 is held in place by collar 354.

The lower cutting finger assembly 306, as shown by FIGS. 17 and 18, which provides the first thread or yarn cut in the

splicing operation, is comprised of air cylinders 370 and 372 mounted on a support bracket 373. Pistons 374 and 376 are slidably mounted in the respective air or fluid cylinders 370 and 372. The clamping piston 374 has a link arm 378 also preferably of a sleeve type construction secured thereto by pin means 382. The cutting piston 376 is connected to linkage 384 by suitable pin or screw means. Linkage 384 is connected to a second angular linkage 386 by a screw or pin means 388. Angular linkage 386 is urged against link arm 378 by spring means 390 which surrounds a shaft 389. Shaft 389 is inserted through the aperture or sleeve in link arm 378 and the aperture or channels in the angular linkage 386, clamp plate 391 and stationary thread holder 394. If desired, the section of the shaft passing through second angular linkage 386 can have the same angular configuration to match the configuration of the aperture in second linkage 386 as was mentioned in the upper cut finger assembly. The spring means 390 is held in place by means of a collar 392. The entrance of air or fluid into cylinder 370 and 372 causes the respective clamping piston 374 and cutting piston 376 to move. When clamping piston 374 is activated, link arm 378 is moved causing clamp plate 391 to function in the manner shown in FIGS. 21a-h. When the cutting piston 376 is activated the linkage turns or rotates shaft 389 working scissor blade 396. Scissor blade 396 turns or rotates cutting the thread or yarn while thread holder 394 remains stationary and supported by lower cut finger assembly housing 398. It should be noted that a spring post 397 and spring 399 which is secured to the post 397 and apparatus housing has the same function as previously mentioned spring post 325 and spring 327. It should also be noted that lower clamp finger assembly 302, which cooperates with the lower cut finger assembly 306, as shown by FIGS. 14 and 21a-h, is constructed identical to the above discussed finger assembly.

35 300. The clamping and cutting finger assemblies cooperate with the wrapping wheel assembly to wind the filament around the threads or yarn during the splicing cycle.

40 The automatic splicing apparatus as shown by FIGS. 21a-h and 22 is preferably designed to provide a splice S of three-eighth inch with 40 to 62 $\frac{1}{2}$ wraps of filament. The clamping and cutting fingers of the apparatus are numbered as previously identified in the application for ease in determining the action of the parts shown in FIG. 21. In addition to wrapping 45 the splice, the cut ends of the thread or yarn Y, Y' are overwrapped by one-sixteenth of an inch beyond each cut thread end giving a total splice wrap of one-half inch.

50 Since the wrapping wheel assembly and the cutting and clamping finger assemblies have some physical thickness, it is not possible to wrap the thread or yarn up to the point where it is to be cut, and then cut it.

55 The cutting operation must be performed when the cutters are approximately one-eighth inch away from the center of the wrapping wheel as this cannot be done at the beginning of the splicing cycle as shown in FIG. 21a, because the threads or yarns must be held in place until they are partially wrapped.

60 The wrapping wheel assembly remains in position and the threads or yarn move down one-quarter inch, up one-half inch and down one-quarter inch to the starting point, to accomplish the preferred one-half inch of filament wrapping. FIG. 21 shows the movement of the thread through the wrapping wheel and the part identification of the apparatus involved. The number of filament wraps as shown in FIGS. 21a-h and 65 22 is based on the minimum number of 40 for illustration. The start of the splicing cycle, as shown by FIGS. 21a, beings when the threads or yarn Y and Y' are placed in parallel arrangement in the wrapping wheel assembly. The yarn or thread Y and Y' is held stationary for 3 $\frac{1}{2}$ wraps as shown by 21b whereupon the yarn moves down one-sixteenth inch for 6 $\frac{1}{2}$ wraps, as shown by FIG. 21c. The yarn or thread then travels upward one-sixteenth inch above the center of the wheel assembly. At this point, as shown by FIG. 21d, the first yarn or thread Y is cut at a point one-eighth inch below the center of the wrapping wheel assembly by the scissor blade 396 of lower

cut finger assembly 306 with ten wraps of filament holding the two threads or yarn Y, Y' together. The center of the splice S continues to rise until it is one-quarter inch above the center of the wrapping wheel and has 15 wraps of filament, as shown by FIG. 21e. The splice remains in this position while another 1 1/2% wraps are applied and the first cut end has been overwrapped. The center of the splice then starts down until it is one-sixteenth inch below the center of the wrapping wheel assembly and at this point the second yarn or thread Y' is cut one-eighth inch above the wrapping wheel center, as shown by FIG. 21f, by scissor blade 329 of upper cut finger assembly 304. The yarn or thread continues downward until the splice center is one-quarter inch below the wheel center where 1 1/2% wraps of filament are applied, as shown by FIG. 21g, and rises until the splice center is again on the wheel center. After an additional 1 1/2% wraps are applied, the wrapping wheel stops and the spliced yarn is released, as shown by FIG. 21h, thereby ending the splicing cycle. It should be noted that during the splicing cycle one end of the filament is being held by the filament holder assembly 500.

When the wrapping wheel assembly 100 stops, the drive motor is declutched, and the drive shaft brake 245 is applied. As shown by FIGS. 1, 2 and 14 when brake 245 is disengaged or released, air or fluid enters cylinder 400 forcing piston 402 outward which drives or carries a toothed rack 404 forward. The piston 402 is secured to rack 404 by any suitable means which will allow the rack to be carried by the piston. As an example, but not to be limited to such example, the piston 402 can be secured to an arm 406 which is secured to rack 404 by bolts 408. The forward motion of rack 404 causes the rack teeth 405 to engage and drive or rotate the positioning pinion gear 240, causing the roller clutch 246 to engage the output shaft 222 and rotate the wheel drive gear 204. As shown by FIG. 2, as soon as the rack 404 starts to move, it releases latch 410 which is urged inward by spring 412 and swings toward wheel drive gear 204, where it strikes pin 238 projecting from the bottom of wheel drive gear 204 and closes switch SW7. When switch SW7 is closed it indicates that the wrapping wheel assembly is in its correct position. The piston 402 of the air or fluid cylinder 400 later retracts carrying toothed rack 404 with it, but the preferably 20-toothed positioning pinion gear 240 turns freely about the output shaft 222 on which positioning pinion gear 240 is mounted, because the roller clutch 246 inside pinion gear 240 only allows the 20-toothed pinion gear 240 to turn the output shaft 222 in one direction. It should be noted that the 200-toothed positioning pinion gear 240 does not revolve when the motor is driving the wrapping wheel assembly 100. At this time air or fluid is applied to cylinder 604 to move the spliced thread or yarn Y, Y' 1 7/16 inches from the center of the wrapping wheel assembly 100. Simultaneously, the filament holder assembly 500 which is shown by FIGS. 23 and 24 is normally in a position below the wrapping wheel as shown in FIGS. 13 and 25, moves with the sliding block 501. The filament holder mechanism has two functions. It must grip and hold the filament for the subsequent splicing operation and cut the filament to the previous splice.

FIG. 26 shows a perspective view of the automatic splicer apparatus and filament holder assembly. When sliding block 501 moves forward, as shown by FIG. 25, link 502 secured to the filament holder plate 403 at 405 causes the filament holder assembly 500 to move or rotate on pin means 507 into the open segment portion 137 of the wheel wrapping assembly. As shown by FIG. 26 while the filament holder assembly 500 is carried forward, a cam 504 rotatably mounted by pin means 509 on the filament holder assembly 500 strikes the front edge of cam plate 506 causing cam 504 to deform spring means 513 and strike dog 511. The dog 511 then contacts outer shaft cam 508 and pushes against it causing the outer shaft 510 to rotate in relation to inner shaft 512. The rotation of the outer shaft 510 causes the movable clamp scissor blade 516 to open in relation to the stationary scissor 518 and stationary clamp 520. The blade assembly 517 is held to

the assembly by clamp means 522 and collar or clip means 524. The blades of assembly 517 are then around the filament 122 which is now extended between the wrapping wheel center and the wrapped threads. As shown by FIG. 25, when the action of the piston 610 carries the cam 504 past cam plate 506, the spring means 513 and outer shaft spring means 526 urge the outer shaft 510 back to its original position causing the blades to shut, cutting the filament at the forward blade 518 and clamping it at the rear clamp 520 simultaneously. It should be noted the filament is gripped by the rear clamp 520 by allowing the filament to enter the apex of position enabling the rounded edge of the rear clamp and cutting scissor 516 to grip the filament in the V formed by the blades. The lowest linear velocity of the moving blade 516 occurs at this apex of position. The piston 610 of cylinder 604 continues its travel to a distance preferably 1 1/4 inches from the center of the wheel to complete its stroke, and actuates switch SW8. This action causes the clamping fingers 300 and 302 to release the spliced thread and the air cylinder piston to return to its normal position. During this return stroke the filament holder also returns to its normal position, retaining its hold on the filament 122. At the completion of the return, switch SW3, as shown by FIG. 13, is actuated by activator pin 611 which is carried by block 501 causing the automatic carrying head motor to restart and the automatic splicing machine head to continue its travel along the way station.

The electro-pneumatic sequence of events which occurs during one cycle of operation is as follows.

Reference is now made to FIG. 27 which shows a circuit suitable for controlling operation of this machine begins when the lever operated by the splicing machine cam closes switch SW1A, completing a current path through relay CR1 via normally closed switch CR5B. The passage of current through relay CR1 causes its normally closed switch CR1B to open, thus interrupting the current path through relay CR2. Switches CR2A, CR2B, and CR2C then open in response to this interruption, disconnecting the drive motor 612 from the three-phase voltage source previously connected to it.

The passage of current through relay CR1 also causes its controlled, normally open switch CR1A to close and this completes a current path through solenoid valve SV1, which responds by allowing air or fluid to be supplied to the clamping cylinders 310, 340, 341 and 370 which then clamp the threads or yarn Y, Y' in position. The closing switch CR1A also permits current to flow through time delay relay TR1 which, after a short delay, closes its normally open, controlled switch TR1A which in turn completes a current path through wind motor 614 via normally closed switches CR3B and CR6A. Wind motor 614 then begins rotating timing cam plate assembly 275. One of the rotating cam plates in the cam plate assembly immediately closes switch SW4A and at the same time opens switch SW4B. When the wind motor has rotated the cam plate assembly 37 1/2°, one of the cam plates opens switch SW6 and when the cam plate assembly has rotated 86°, a cam plate similarly closes switch SW5 completing a current path through solenoid valve SV3 which then opens the air to cutting cylinder 372 to make the first cut of the threads held by the lower cut finger assembly 306, upper cut finger assembly 304, and clamp finger assemblies 300 and 302. Next one of the cams recloses switch SW6 when rotated 206° so that current flows through solenoid valve SV4 via closed switches SW5 and SW6. Solenoid valve SV4 then permits air or other fluid to enter cutting cylinder 312 to make the second cut of thread or yarn Y, Y'.

The closing of switch SW6 also completes a current path through relay CR3 which then causes its normally open switch CR3A to close, completing a latching current path around switch SW5. The passage of current through relay CR3 also opens normally closed switch CR3C, which is connected in parallel with normally open and now closed switch SW4A. At a 360° of rotation of the cam plate assembly 275 a cam plate opens switch SW4A and switch SW5A thus cutting the current path through wind motor 614 which ceases to rotate the cams.

Relay CR3 remains activated by the current path through its controlled switch CR3A.

The reclosing of switch SW4B similarly completes a current path through relay CR4 which responds by closing its normally open switch CR4A which in turn completes a current path through brake 245 which has a capacitor 618 connected in parallel with it, and which is supplied with d.c. current via full wave rectifier 620. The passage of current through relay CR4 also causes switch CR4B to close completing a current path through time delay relay TR2. The passage of current through relay TR2 closes its controlled switch TR2A which thus completes a current path through solenoid valve SV2 which then opens allowing air or fluid to enter cylinder 400 which rotates the wheel drive gear 204 by positioning gear pinion 240 to turn the wrapping wheel assembly 100 to the proper position. At that position wheel drive gear pin 238 hits a lever 410 closing switch SW7.

The closing of switch SW7 results in current flowing through the solenoid valve SV5 which then opens allowing fluid or air to enter cylinder 604 of the filament holder assembly 500, and also to push the sliding block 501 with the clamp fingers and the cylinder holder forward, cutting the filament and holding the filament attached to the bobbin 120 of the wrapping wheel assembly 100. Next, switch SW3 is closed by the sliding block 501 as it is pushed forward and opens. The closing of switch SW8 activates relay CR5 which then closes its normally open, controlled switch CR5A and similarly opens its normally closed controlled switch CR5B. The closing of switch CR5A completes a current path around switch SW8, and the opening of switch CR5B interrupts the current path through relay CR1. The opening of switch CR1A deactivates all of the solenoid valves and air or fluid is released from all of the cylinders. The opening of switch CR1A further deactivates relay CR3 resulting in contact CR3B closing and CR3A opening. As the block 501 retracts, switch SW3 recloses re-completing the current path through relay CR2 which recloses its controlled normally open switches CR2A, CR2B and CR2C. The drive motor 612 of the splicing machine head restarts and the lever keeping switch SW1A closed shifts to permit switch SW1A to reopen. The opening of switch SW1A interrupts the current path through relay CR5 which then opens its controlled latching switch CR5A and switch CR5B, thus completing the splicing cycle.

When a new spool of filament is being installed or for any reason a filament is not held in the filament holder, it is necessary to energize solenoid valve SV5 to apply fluid or air to cylinder 604 to cause the filament holder assembly 500 to recycle in order to grip the filament. This should only be done before the wrapping part of the cycle is started or after it is finished.

Switch SW9 is provided to stop all motors at any time during the cycle. If switch SW9 is operated during the wrapping cycle, the current flows through relay CR6 which responds by opening its normally closed switches CR6A, CR6B and CR6C which interrupts the three-phase supply which it connects to the drive motor 612. The now open switch CR6A also interrupts the current path through motor 614. If switch SW9 is closed anytime during the wrapping cycle, wrapping of motor 614 stops but the clamping fingers do not release the thread. If the switch SW9 is closed at any time before or after the wrapping cycle, the splicing apparatus drive motor 612 stops and the pushbutton PB1 becomes operative, to permit the filament holder to be cycled.

The above-described apparatus for splicing yarns in textile plants eliminates the age-old knot burling operation since there is no fabric deformation by the bulk of the knot or its tails and since the splicing thread is unneeded after the yarn is tight within the woven fabric, the splicing thread can be dissolved out in subsequent fabric treating steps because it is water soluble. Burling, which is removing defects from a piece of cloth, causes a considerable expense annually to a textile manufacturer. If a knot is not burled, a shearing machine will oftentimes cut a hole into the fabric. The present apparatus

utilizing water soluble wrapping threads can completely eliminate the need to burl knots.

It will be realized that the foregoing specific embodiments disclosed and described illustrate the principles of the invention and are subject to some change without departing from such principles. For example, a relatively non-soluble wrapping material may be preferred in the case of knit goods; whereas a soluble yarn is desired in the case of woven goods where the weave can bind in the spliced ends. Moreover, changes are contemplated in the wrapping material, which may be of the spun yarn type or may be in film, multifilament or monofilament form. Moreover, the wrapping material may be water soluble as already indicated or may be solvent soluble such as a vinyl acetate material, or may be relatively inert, such as glass which may be desired for certain aerospace uses. Additionally, other forms of motive power are visualized, such as air motors, etc.

Although the present invention has been described and illustrated in connection with various embodiments, it is to be understood that modifications and variations may be resorted to without departing from the spirit of the invention, as those skilled in this art will readily understand. Such modifications and variations are considered to be within the purview and scope of the present invention as defined by the appended claims.

What is claimed is:

1. An automatic splicing apparatus for wrapping filament around yarn comprising a housing, drive means mounted in said housing, said drive means operating a filament wrapping wheel, said filament wrapping wheel having a filament supply mounted thereon, clamping and cutting means secured to said housing to hold and cut said yarn being wrapped, a filament holder means mounted to said housing, said filament holder means retaining an end of said filament during a wrapping cycle and said filament holder means having means for cutting said filament at the end of said cycle, and tensioning means carried by said filament wrapping wheel for maintaining a tension on filament being drawn from said supply.
2. An automatic splicing apparatus as claimed in claim 1 wherein said drive means includes an auxiliary drive means having cam means to provide for vertical oscillation of said clamping and cutting means.
3. An automatic splicing apparatus as claimed in claim 2 wherein said auxiliary drive means comprises a drive shaft, said drive shaft being mounted in a plurality of roller bearing means, said roller bearing means being secured to a housing, means to rotate said drive shaft, a worm secured to said auxiliary drive shaft, said worm engaging a worm gear to rotate said worm gear, said worm gear being secured to a shaft, said shaft being mounted in a plurality of roller bearing means positioned in said housing, a drive gear secured to said shaft, said drive gear cooperating with a cam plate assembly to turn said cam plate assembly.
4. An automatic splicing apparatus as claimed in claim 3 wherein said cam plate assembly comprises a cam gear secured to a cam shaft, a cam hub mounted on said shaft, a plurality of cam plates mounted on said cam hub, said cam plates being separated by a plurality of cam spacers, and means to secure said plurality of cam plates and cam hub to said cam gear.
5. An automatic splicing apparatus as claimed in claim 4 wherein said cam shaft has separate cam means secured thereto.
6. An automatic splicing apparatus as claimed in claim 1 wherein said clamping and cutting means to hold and cut said yarn being wrapped comprises a plurality of cut finger assemblies and a plurality of clamp finger assemblies.
7. An automatic splicing apparatus as claimed in claim 1 wherein said wrapping wheel assembly comprises a drive body assembly having an insert plate assembly removably mounted thereto, said insert plate assembly having a filament supply means mounted thereon.

8. An automatic splicing apparatus as claimed in claim 7 wherein said drive body assembly is substantially C-shaped and the outer surface of the drive body assembly has gear means.

9. An automatic splicing apparatus as claimed in claim 8 wherein said gear means are removable gear sections.

10. An automatic splicing apparatus as claimed in claim 7 wherein said insert plate assembly has a substantially pie-shaped section removed.

11. An automatic splicing apparatus as claimed in claim 7 wherein said filament supply means comprises a mount secured to said insert plate assembly, said mount having a support arm extending therefrom, a bobbin mounted on said support arm, and adjustable tension means to provide tension on a filament coming from the bobbin.

12. An automatic splicing apparatus as claimed in claim 11 wherein said bobbin has a protective casing mounted thereon.

13. An automatic splicing apparatus for wrapping yarn with filament comprising a housing, drive means mounted in said housing, said drive means being positioned to rotate a wrapping wheel assembly, said wrapping wheel assembly having a filament supply mounted thereto, a filament holder assembly mounted in said housing, said filament holder assembly being provided with means to retain the filament under tension during a splicing cycle and means to cut the filament at the end of the splicing cycle, means to hold and cut said yarn being wrapped with filament, and means to automatically operate said wrapping wheel assembly, filament holder assembly and holding and cutting means during a splicing cycle.

14. An automatic splicing apparatus as claimed in claim 13 wherein said drive means comprises a drive shaft, means to turn said drive shaft, a gear secured to said drive shaft, said gear engaging a second gear when said drive shaft is rotated, said second gear being secured to an output shaft, said output shaft having a drive wheel gear secured thereon, said drive wheel gear engaging a plurality of pinion gears, said plurality of pinion gears engaging and driving said wrapping wheel assembly.

15. An automatic splicing apparatus as claimed in claim 14 wherein said first gear and said second gear are miter gears.

16. An automatic splicing apparatus as claimed in claim 15 wherein said gear means comprises a positioning pinion gear mounted on an output shaft, said positioning pinion gear having roller clutch means allowing said pinion gear to rotate freely around said output shaft in one direction and to engage and turn said output shaft in the other direction causing a wheel drive gear secured to said output shaft to rotate.

17. An automatic splicing apparatus as claimed in claim 16 wherein said wheel drive gear has a protruding pin positioned to strike a latch when said wheel drive gear is rotated by said positioning pinion gear, said latch closing switch means indicating the wrapping wheel assembly is positioned correctly.

18. An automatic splicing apparatus as claimed in claim 14 wherein said gears are secured to said drive shaft and output shaft by key means.

19. An automatic splicing apparatus as claimed in claim 14 wherein said wheel drive gear has a pin projecting therefrom.

20. An automatic splicing apparatus as claimed in claim 13 wherein said drive means has a wrapping wheel assembly positioning means, said wrapping wheel assembly positioning means positioning said wrapping wheel assembly in substantially the same position at the start of each splicing cycle.

21. An automatic splicing apparatus as claimed in claim 20 wherein said wrapping wheel assembly positioning means comprises a fluid cylinder secured to said housing, a piston slidably mounted in said fluid cylinder, a toothed rack carried by said piston, said toothed rack engaging gear means to turn said wrapping wheel assembly to a predetermined position.

22. An automatic splicing apparatus as claimed in claim 13 wherein said means to hold and cut said yarn being wrapped with filament comprises a plurality of cut finger assemblies and a plurality of clamp finger assemblies.

23. An automatic splicing apparatus as claimed in claim 22 wherein each of said cut finger assemblies comprises a plurality of fluid cylinders, each of said fluid cylinders having a piston slidably mounted therein, linkage secured to each said piston, said linkage connecting each of said pistons to cutting and clamping means.

24. An automatic splicing apparatus as claimed in claim 23 wherein one of said pistons activates a clamping means and another of said pistons activates a cutting means.

25. An automatic splicing apparatus as claimed in claim 22 wherein at least one of said finger assemblies is an upper cut finger assembly, said upper cut finger assembly comprising a plurality of fluid cylinders, each of said fluid cylinders having a piston slidably mounted therein, one of said pistons being secured to link arm, the other of said pistons being connected to a shaft by a plurality of links, said shaft extending through one of said plurality of links, said link arm and a stationary thread holder secured to a housing, said shaft being able to be rotated by the action of the other of said pistons moving said plurality of links to turn a blade secured to said shaft and bordering said stationary thread holder.

26. An automatic splicing apparatus as claimed in claim 22 wherein at least one of said cut finger assemblies is a lower cut

25 finger assembly, said lower cut finger assembly comprising a plurality of fluid cylinders, each of said fluid cylinders having a piston slidably mounted therein, one of said pistons being secured to a link arm having an aperture therethrough, the other of said pistons being connected to a plurality of links, 30 one of said links having an aperture therethrough, a shaft extending through said link aperture, said link arm aperture and a stationary thread holder secured to a housing, said shaft being able to be rotated by the action of the other of said pistons moving said plurality of links to turn a blade secured thereto and bordering said stationary thread holder.

27. An automatic splicing apparatus as claimed in claim 22 wherein each of said clamp finger assemblies cooperates with a cut finger assembly to hold yarn to be spliced, each of said clamp finger assemblies comprising a fluid cylinder, a piston

40 slidably mounted in said fluid cylinder, and linkage secured to said piston, the other end of said linkage being secured to clamp means.

28. An automatic splicing apparatus as claimed in claim 27 wherein said clamp means comprises a stationary thread holder having an aperture therethrough, said stationary thread holder being secured to a clamp finger housing, a link arm having at least one aperture therein, a shaft inserted through one of said link arm apertures and said stationary thread holder aperture, said shaft having a clamp plate secured thereto, means to prevent said shaft from rotating inside said link arm and spring means surrounding a portion of said shaft and contacting said link arm.

29. An automatic splicing apparatus as claimed in claim 28 wherein said means to prevent said shaft from rotating inside said link arm is a pin inserted into said link arm aperture and a coaxially aligned shaft aperture.

30. An automatic splicing apparatus as claimed in claim 13 wherein said filament holder assembly comprises a stationary inner shaft, a rotatably outer shaft surrounding said inner shaft, spring means secured to said outer shaft to urge said outer shaft into a set position, cam means mounted on said outer shaft, said cam means acting in cooperation with a cam plate to rotate said outer shaft and cutting means mounted on said outer shaft.

31. An automatic splicing apparatus as claimed in claim 30 wherein said cutting means comprises a stationary scissor blade secured to said inner shaft, a stationary clamp mounted on said outer shaft, said stationary clamp being secured to said stationary scissor blade and a movable scissor blade mounted on said outer shaft and positioned between said stationary clamp and said stationary scissor blade.

32. An automatic thread splicing apparatus for wrapping filament around yarn comprising a housing, drive means mounted in said housing, said drive means being positioned to

rotate a wrapping wheel assembly, said wrapping wheel assembly having a filament supply mounted thereto, a filament holder means secured to said housing, said filament holder means retaining said filament during a splicing cycle and cutting said filament at the end of the splicing cycle,

a plurality of cut finger assemblies and clamp finger assemblies mounted on said housing to hold and cut said yarn being wrapped; and

circuit means for controlling said cut finger assemblies and clamp finger assemblies during a splicing cycle.

33. An apparatus as claimed in claim 32 wherein said yarn includes a first piece having a first severed end and a second non-severed end and a second piece having a first severed end and a second non-severed end, wherein said clamp finger assemblies include a first assembly for holding said first piece adjacent said second end and a second assembly for holding said second piece adjacent said second end, wherein said cut finger assemblies include a first assembly for holding said first piece adjacent its severed end and adjacent the non-severed end of said second piece and for cutting the severed end of said first piece and a second assembly for holding said second piece adjacent its severed end and adjacent the non-severed end of said first piece and for cutting the severed end of said second piece, a source of fluid above atmospheric pressure and control means operatively associated with said circuit means for controlling the application of fluid pressure from said source to said first and second assemblies, whereby wherein said first and second assemblies of said clamp finger assemblies and said first and second assemblies of said cut finger assemblies operate to hold and to cut respectively when connected to said a source of fluid at a pressure above atmospheric pressure, and wherein said circuit means includes means for applying said source to said assemblies.

34. An apparatus as in claim 33 wherein said circuit means includes a first relay which, when activated connects said source to said first and second assemblies of said clamp finger

assemblies and to said first and second assemblies of said cut finger assemblies to hold said first and second pieces, a second relay which, when activated, connects said source to said first assembly of said cut finger assemblies for cutting the non-severed end of said first piece and a third relay which, when activated, connects said source to said second assembly of said cut finger assemblies for cutting the non-severed end of said second piece.

35. An automatic splicing apparatus for wrapping filament around yarn ends held in an overlapping relationship comprising:

wrapping means for wrapping filament around said yarn ends so as to form a filament wrap around the yarn ends which extends for a distance along the overlapped ends to retain the yarn ends together,

clamping means for receiving and holding said yarn ends in an overlapping relationship during the wrapping,

filament supply means mounted in an enclosed housing on said wrapping means for supplying filament,

adjustable tension means positioned adjacent said filament supply means for applying a uniform tension on the filament during the wrapping,

drive means operatively associated with said wrapping means for rotating said filament supply means around said overlapped yarn ends so that filament is drawn from said filament supply means through said tension means thereby producing a tensioned splice,

yarn cutting means operatively associated with said wrapping means for cutting said yarn ends back so that the cut ends can be overwrapped with said filament, and

filament cutting means for cutting said filament after the wrapping has been completed so that the portion of filament used in producing the splice is separated from said filament supply means.
